CLAIM

The ornamental design for a floor polishing broom, as shown and described.

DESCRIPTION

FIG. 1 is a front right side perspective view of a floor polishing broom which embodies our design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown are for illustrative purposes only and form no part of the claimed design.

The use of the discontinuous rendering of the mop handle represents indeterminate length.
